UNITED STATES PATENT OFFICE

LEE B. GREEN, OF LAKewood, OHIO

DESIGN FOR A COMBINED STAND AND CASING FOR A DRY-CLEANING MACHINE OR
SIMILAR ARTICLE

Application filed January 28, 1931. Serial No. 38,470. Term of patent 14 years.

To all whom it may concern:

Be it known that I, LEE B. GREEN, a citizen of the United States, residing at Lakewood, in the county of Cuyahoga and State of Ohio, have invented a new, original, and ornamental Design for a Combined Stand and Casing for a Dry-Cleaning Machine or Similar Article, of which the following is a specification, reference being had to the accompanying drawing, forming part thereof.

In the drawing, the figure is a perspective view of a combined stand and casing for a dry-cleaning machine or similar article, showing my new design.

I claim:

The ornamental design for a combined stand and casing for a dry-cleaning machine or similar article, substantially as shown.

LEE B. GREEN.
